CONSTANT D.-C. VOLTAGE OUTPUT CIRCUIT

Edward John Diebeld, Ardmore, Pa., assignor to I-T-E
Circuit Breaker Company, Philadelphia, Pa., a corporation of Pennsylvania

Filed July 27, 1955, Ser. No. 524,778

2 Claims. (Cl. 321—16)

My invention relates to a circuit for supplying a constant D.-C. output voltage from a source of variable alternating voltage, and more specifically to a constant D.-C. voltage output circuit which utilizes the characteristics of saturable type reactors, which provide a constant number of volt seconds for any voltage greater than a predetermined magnitude.

This application is a continuation in part of my pending application, Serial No. 312,053, filed September 29, 1952, and now abandoned.

The principle of my invention is to apply the input of an alternating voltage source of variable voltage magnitude to a winding of a saturable type reactor. The saturable type reactor is then so designed as to be too small to be completely unsaturated for the lowest voltage which the alternating current source will ever reach. Therefore, a voltage having a pulse shape, since the reactor will be saturated for a portion of the cycle, will appear on the winding of the saturable reactor which has this alternating voltage applied to it.

As is well known, the volt second area contained in this pulse will have a constant value. That is to say, that if the voltage is of a low magnitude the pulse will be relatively wide and of small magnitude. Conversely, if the alternating voltage is of a high magnitude, the pulse will be of a relatively short duration and will be of a high magnitude. However, it is essential to realize that the area under either of the pulses will be constant. If now this pulse is rectified, in view of the constancy of the area contained in the pulse, it is clear that the average voltage value of the pulse will be constant and will be determined by the design of the saturable reactor which determines the area under the pulse.

This fact becomes apparent when one considers that the average value of the voltage will be equal to the integral of the voltage times the differential of the time, the integral being taken over limits defined by the pulse width. Since this integral merely defines the area under the pulse, which will be constant, then it is seen that the average voltage output for any input voltage magnitude will be constant.

It is however, essential that the connection between the saturable type reactor and the rectifier be a non-reactive type of connection. This becomes apparent when the pulse output of the saturable type reactor to the reactive device is considered as comprising a series of harmonic voltages. Clearly, for different size pulses, which would be obtained with different input voltages, the harmonic content of the pulse would vary. If now a reactance carries this pulse of varying harmonic content, it is obvious that each harmonic would see a different impedance. Therefore, a pulse of variable harmonic content would be attenuated according to the impedance seen by each constituent harmonic, and accordingly, the total output of the sum of each of the attenuated harmonics for different pulse shapes giving a different output voltage after rectification of the pulse.

By meeting the restrictions of a connection which is

2

substantially non-reactive, such as a direct or resistor connection, a selective impedance effect upon the harmonics which comprise any particular pulse would not be affected and the output voltage pulse for any shape would indeed contain a constant area thereby affording a constant D.-C. voltage output.

Accordingly, a primary object of my invention is to provide a novel circuit which will provide a constant D.-C. voltage output from a source of variable alternating voltage.

Another object of my invention is to provide a constant D.-C. voltage output circuit which utilizes the properties of a saturable type reactor.

A still further object of my invention is to provide a constant D.-C. voltage output circuit which utilizes a saturable type reactor wherein the output voltage is determined as a function of the number of volt seconds which is absorbed by the saturable type reactor.

Another object of my invention is to provide a D.-C. output voltage circuit utilizing a saturable type reactor and a rectifier wherein the connection between the saturable type reactor and the rectifier is either a direct connection or a resistive connection.

In the practice of my novel invention as described above, it has been found that there is a very slight variation, which in many applications is negligible, of the D.-C. output voltage for variations in the A.-C. input voltage due to the air reactance of the saturable reactor winding when this reactor is saturated.

That is to say, that although the saturable reactor is in a saturated state a very small voltage will continuously be transmitted from the A.-C. input circuit to the rectifier since the saturated saturable core reactor acts like an air core transformer.

If the application is so critical that even this very small variation cannot be tolerated, I have found that it can be compensated for by providing a small auxiliary transformer in the A.-C. circuit which will induce a voltage into the circuit leading to the rectifier which substantially equally opposed the aforementioned voltage due to the air reactance of the saturable reactor winding for all values of input A.-C. voltage.

Accordingly, another object of my invention is to provide means to compensate for the voltages due to the air reactance of the saturable type reactor which are induced in the rectifier circuit.

Another object of my invention is to provide transformer means in the input A.-C. circuit which will induce a voltage in the circuit leading to the rectifier for bucking down voltage due to the air reactance of the saturable reactor.

Although the D.-C. output of my novel circuit is constant for any output pulse, it should be understood that the R.M.S. output and harmonic content varies widely.

It is, however, necessary in some applications for the R.M.S. input to a load to be substantially constant.

I have found that I can accomplish this end by providing a filter for the output of the rectifier which comprises a high pass filter and a low pass filter. The load circuit, which must carry a direct current of constant magnitude, is connected through the low pass filter and a dummy load having an impedance equivalent to the impedance of the load is connected to the high pass filter.

The rectifier output impedance to the load will therefore be approximately resistive for a full range of harmonic frequencies and the operation of the circuit will not be affected by a frequency selective impedance of any intermediate component of the circuit and the load, in view of its low pass filter will carry a current of a substantially constant R.M.S. value.

Accordingly, another object of my invention is to pro-

vide a high pass filter and low pass filter to the output of my novel circuit.

These and other objects of my invention will become apparent when taken in conjunction with the figures in which:

Figure 1 is a circuit diagram of one form of my novel invention.

Figure 2 shows another form which can be taken by my novel invention.

Figure 3 shows a first, second and third voltage of the variable A.-C. voltage input as plotted against time.

Figure 4 shows the voltage appearing on the current limiting impedance which is in series with the saturable reactor primary winding.

Figure 5 shows the A.-C. voltage as a function of time which appears on the saturable type reactor winding as a voltage pulse for the corresponding three voltages shown in Figure 3.

Figure 6 shows the constant D.-C. voltage output of the rectifier for the three voltages of Figure 3.

Figure 7 shows the circuit of Figure 1 modified to contain means to compensate for the air core inductance of the saturable reactor and high and low band pass circuits for the rectifier output.

Figure 8 is similar to Figure 7 where the filter circuits are slightly modified.

Referring now to Figure 1, an A.-C. voltage of variable magnitude is impressed upon the A.-C. terminals 10 and 11 and this voltage is then impressed upon the series connection of winding 12 of the saturable reactor core 13 and (non-saturable) reactor 20. A second winding 14 is also wound in the core 13 of the saturable reactor to thereby allow a transformer action between the winding 12 and 14 when the core 13 is saturated. The voltage appearing upon the coil 14 is then impressed directly upon a rectifier 15 and the output of this rectifier is then smoothed in any desired manner such as the filter comprising the resistor 21, the capacitor 16 and inductor 17. As will be shown hereinafter, a D.-C. voltage of constant magnitude will appear on the output terminals 18 and 19.

The circuit of Figure 1 is essentially duplicated in the circuit of Figure 2 with several illustrative variations. In Figure 2, the core 13 contains only a single winding 12 which acts as both a secondary winding and a primary winding when the core 13 is unsaturated. Here again, a current limiting reactor 20 is provided. This is to say that whenever the core 13 is saturated, the current due to the alternating voltage impressed upon the terminals 10 and 11 will rise unhampered if a current limiting device is not in the circuit. Obviously, the inductor 20 could have been replaced by another impedance such as a resistor but the choke action is more desirable since it dissipates less power.

Another modification shown in Figure 2 is in the positioning of resistor 21. Here, as in the case of Figure 1, resistor 21 serves a current limiting function. Note, however, that a resistor will not exert a selective impedance effect upon the voltage pulses appearing on the winding 12. Hence, when the shape of the pulse appearing on winding 12 is varied due to a variation in the input voltage the area under the pulse will remain unaltered and the average D.-C. voltage which appears on the output terminals 18 and 19 will be constant.

The operation of the circuits of Figures 1 and 2 may now be described in conjunction with the voltage time diagrams shown in Figures 3, 4, 5 and 6. More specifically, Figure 3 shows a first voltage V_1 which is assumed by the alternating voltage at the terminals 10 and 11, a second and higher voltage V_2 which may be the voltage assumed at another time at the terminals 10 and 11 and a still higher voltage V_3 .

When the voltage V_1 of Figure 3 appears across the winding 12 of Figure 1 or 2, it is clear that the core 13

will remain unsaturated for the interval of time defined by the length of the pulse V_{21} shown in Figure 5.

Since the circuit is completely reactive, the current will be 90° out of phase with the voltage and therefore at both the beginning of the voltage cycle and at the end of the voltage cycle and the core 13 will be saturated, thereby requiring the shape of the pulse V_{21} to be substantially symmetrical about the peak of voltage V_1 .

The area under the pulse V_{21} of Figure 5 is, of course, determined by the saturable reactor design which is so constructed as to absorb only a certain predetermined number of volt seconds. If now the A.-C. voltage is increased to achieve the value V_2 of Figure 3, it is clear that in view of this higher voltage, and in view of the fact that the saturable reactor can absorb only a predetermined number of volt seconds, that the voltage pulse V_{22} appearing on the winding 14 as shown in Figure 5 will be higher and, therefore, of a decreased duration. It is, however, essential to note that the voltage time area defined by the pulse is exactly equal to the area defined by the pulse of voltage V_{21} of Figure 5.

It then follows that if the voltage is further increased to the value V_3 of Figure 3, that the voltage V_{23} of Figure 5 which is of higher magnitude but shorter duration will appear on the saturable reactor winding.

During the interval that the saturable reactor is saturated, the input voltage, as shown in Figure 4, appears across the current limiting reactor 20 of Figure 1 or 2. Hence, in the case of the voltage V_1 of Figure 3, a very small voltage V_{11} appears on reactor 20 at the beginning of the cycle until the saturable reactor unsaturates. The A.-C. voltage then transfers to the much higher impedance of the unsaturated saturable reactor as shown by V_{21} of Figure 5. Upon the subsequent saturation of the saturable reactor, the voltage as shown in Figure 4 once again appears on the current limiting impedance 20 of Figures 1 and 2.

Similar remarks can be directed to the case of the input voltage V_2 of Figure 3 on which the voltage V_{12} of Figure 4 appears on the current limiting impedance and the case of the voltage V_3 in which the voltage V_{13} appears on this current limiting impedance.

It is important to note that in the case of Figure 1, the voltage pulse is transformed into the winding 14 so long as the core 13 is unsaturated and the voltage pulse is directly transmitted to the input terminals of rectifier 15. In the case of the circuit of Figure 2, the voltage pulse appearing on the winding 12 is transmitted to the rectifier input terminal through a resistor; this non-reactive type connection between the transducer winding and rectifier as was noted above, is essential since it does not allow the selective impedance effect of a reactance to be exerted upon the transmitted pulse which is being put on the rectifier input terminal.

After the rectifying action of the rectifier 15 of Figure 1 or 2, the voltage appearing at the D.-C. terminals of the rectifier is as shown in Figure 6, the average D.-C. voltage being shown by the dot-dash line of constant magnitude. Note that the average voltage is constant whether it is due to the short and wide pulse V_{31} , the tall thin pulse V_{33} , or the intermediate pulse V_{32} . This is due of course, to the fact that the area contained under the voltage pulses V_{31} , V_{32} and V_{33} are exactly equal, this area being a function of the design of the saturable reactor core 13 and its associated windings.

That the average value of pulses having a different shape but constant area is constant may be seen from the following consideration. The definition of an average value is the integral of the voltage times the derivative of the time. This integral gives the area under the pulse. Therefore, two pulses having a constant area will, of necessity, have a constant average value.

It is to be noted that the root mean square value of the voltage at the terminals of the winding 14 in Figure 1 and the terminal 21 in Figure 2 varies as the input

voltage varies. Once again, this may be explained in the definition of the root means square value, and reference to the voltages shown in Figure 6. The root means square value of the voltages will be equal to the integral of the voltage squared times the derivative of the time. Therefore, even though the pulses have a constant area, the difference in the instantaneous voltage squared times the derivative of the time summed up over the length of the pulse will obviously give completely different value for different pulse shapes.

In the previous description of my novel invention, I have shown both Figures 1 and 2 as utilizing a bridge type rectifier. It is, however, clear that any rectifying means could be utilized in the operation of my novel invention. Similarly, the current limiting resistor 21 of Figure 2 is applied to the circuit of Figure 1, after the rectifier. This resistor is necessary to prevent an excessive inrush current through the rectifier 15 into the capacitor 16. Similar remarks can be directed to the use of a single winding 12 as shown in Figure 2 which would act as both a primary winding and secondary winding when the core 13 is unsaturated. That is, it is merely a design expedient which determines the use of a single winding or an isolated primary and secondary winding 12 and 14 as shown in Figure 1.

Figures 7 and 8 show two refinements of the original circuits in Figures 1 and 2. These circuits operate the same way as the other circuits, except that they have two compensations to provide a more nearly constant D.-C. voltage over a wide variation of the A.-C. voltage.

In Figures 7 and 8, the choke 24 replaces the choke 20 of Figures 1 and 2. This choke absorbs the voltage shown in Figure 4, on the winding 22 which is in series with the saturable reactor winding 12. In the winding 23 on a low voltage proportional to the one on winding 22 is induced. In the windings 12 and 14 a voltage is induced according to Figure 5. However, the volt-time area of this voltage is not exactly constant because the mutual air-core inductance of the coils 12 and 14 induces a small additional voltage in coil 14; this additional voltage being proportional to the current in the coil 12. Since the voltage on coil 22 increases greatly when the voltage on the terminals 10—11 increases, which also causes the current to increase, the undesirable additional voltage in coil 14 is approximately proportional to the voltage on coil 22. As the circuits in Figures 7 and 8 are connected, the small voltage induced in coil 23 subtracts from the voltage induced in coil 14 which compensates for the additional voltage caused by the air core inductance.

Another variation over Figures 1 and 2 is in the filter. In Figure 7 the filter consists of a high-pass filter consisting of two capacitors 25 and 26 and a reactor 27. This filter is terminated in a resistor 28 which has the same resistance as the load 32. If the voltage output of the rectifier is not distorted (V_{31} in Figure 6) the high frequency components of this voltage are small and the current absorbed by this high-pass circuit is very low. When the voltage output of the rectifier 15 is greatly distorted (V_{33} in Figure 6) then the high-pass circuit carries a high harmonic current which is absorbed by the resistor 28.

The load circuit, which must carry a direct current of constant magnitude, is connected through a low pass filter consisting of the reactors 29 and 31 and the capacitor 30. The reactor 31 is not necessarily a real coil but is usually represented by the inherent inductance of the D.-C. load. This low-pass circuit keeps the current through the load 35 at a constant value.

By adding a low-pass filter to the load and a high-pass filter to a dummy resistor 28 we obtain a rectifier output impedance which is constant and approximately resistive for the full range of frequencies from D.-C. to infinite. Therefore, the operation of the constant voltage circuit is not affected by a frequency selective impedance of any interval component of the circuit.

In Figure 8 the circuit is made according to the same principle, except that the high-pass and low-pass filters are more elaborate: The high-pass filter consists of the capacitors 25, 26 and the inductance-capacitance circuit 27—33. The low-pass filter consists of the reactors 21 and 31 and the inductance-capacitance circuit 34—30. This has the advantage that the combined impedance as seen from the rectifier terminals is more nearly and constant for the full range of frequencies.

In the foregoing, I have described my invention only in connection with preferred embodiments thereof. Many variations and modifications of the principles of my invention within the scope of the description herein are obvious. Accordingly, I prefer to be bound not by the specific disclosure herein but only by the appending claims.

I claim:

- 25 1. A circuit to supply a constant D.-C. output voltage from a variable A.-C. input; said circuit comprising a saturable type reactor and a rectifier; said saturable type reactor having a primary and a secondary winding and a core of rectangular hysteresis loop material; said secondary winding directly connected to the A.-C. side of said rectifier and said primary winding connected in series with said variable A.-C. source and filtering means being connected to the D.-C. terminals of said rectifier, said filter means comprising a high pass filter and a low pass filter, said low pass filter being connectable to a D.-C. load, said high pass filter being connectable to a dummy load.
- 30 2. A circuit to supply a constant D.-C. output voltage from a variable A.-C. input; said circuit comprising a saturable type reactor and a rectifier; said saturable type reactor having a primary and a secondary winding and a core of rectangular hysteresis loop material; said secondary winding directly connected to the A.-C. side of said rectifier and said primary winding connected in series with said variable A.-C. source and filtering means being connected to the D.-C. terminals of said rectifier, said filter means comprising a high pass filter and a low pass filter, said low pass filter being connectable to a D.-C. load, said high pass filter being connectable to a dummy load.
- 35 3. A circuit to supply a constant D.-C. output voltage from a variable A.-C. input; said circuit comprising a saturable type reactor and a rectifier; said saturable type reactor having a primary and a secondary winding and a core of rectangular hysteresis loop material; said secondary winding directly connected to the A.-C. side of said rectifier and said primary winding connected in series with said variable A.-C. source and filtering means being connected to the D.-C. terminals of said rectifier, said filter means comprising a high pass filter and a low pass filter, said low pass filter being connectable to a D.-C. load, said high pass filter being connectable to a dummy load.
- 40 4. A circuit to supply a constant D.-C. output voltage from a variable A.-C. input; said circuit comprising a saturable type reactor and a rectifier; said saturable type reactor having a primary and a secondary winding and a core of rectangular hysteresis loop material; said secondary winding directly connected to the A.-C. side of said rectifier and said primary winding connected in series with said variable A.-C. source and filtering means being connected to the D.-C. terminals of said rectifier, said filter means comprising a high pass filter and a low pass filter, said low pass filter being connectable to a D.-C. load, said high pass filter being connectable to a dummy load and transformer means being connected to induce a compensating voltage from the circuit including said primary winding to the circuit including said secondary winding, said compensating voltage being opposed to the voltage induced in said secondary winding due to the air core reactance of said saturable type reactor.
- 45 5. A circuit to supply a constant D.-C. output voltage from a variable A.-C. input; said circuit comprising a saturable type reactor and a rectifier; said saturable type reactor having a primary and a secondary winding and a core of rectangular hysteresis loop material; said secondary winding directly connected to the A.-C. side of said rectifier and said primary winding connected in series with said variable A.-C. source and filtering means being connected to the D.-C. terminals of said rectifier, said filter means comprising a high pass filter and a low pass filter, said low pass filter being connectable to a D.-C. load, said high pass filter being connectable to a dummy load and transformer means being connected to induce a compensating voltage from the circuit including said primary winding to the circuit including said secondary winding, said compensating voltage being opposed to the voltage induced in said secondary winding due to the air core reactance of said saturable type reactor.
- 50 6. A circuit to supply a constant D.-C. output voltage from a variable A.-C. input; said circuit comprising a saturable type reactor and a rectifier; said saturable type reactor having a primary and a secondary winding and a core of rectangular hysteresis loop material; said secondary winding directly connected to the A.-C. side of said rectifier and said primary winding connected in series with said variable A.-C. source and filtering means being connected to the D.-C. terminals of said rectifier, said filter means comprising a high pass filter and a low pass filter, said low pass filter being connectable to a D.-C. load, said high pass filter being connectable to a dummy load and transformer means being connected to induce a compensating voltage from the circuit including said primary winding to the circuit including said secondary winding, said compensating voltage being opposed to the voltage induced in said secondary winding due to the air core reactance of said saturable type reactor.
- 55 7. A circuit to supply a constant D.-C. output voltage from a variable A.-C. input; said circuit comprising a saturable type reactor and a rectifier; said saturable type reactor having a primary and a secondary winding and a core of rectangular hysteresis loop material; said secondary winding directly connected to the A.-C. side of said rectifier and said primary winding connected in series with said variable A.-C. source and filtering means being connected to the D.-C. terminals of said rectifier, said filter means comprising a high pass filter and a low pass filter, said low pass filter being connectable to a D.-C. load, said high pass filter being connectable to a dummy load and transformer means being connected to induce a compensating voltage from the circuit including said primary winding to the circuit including said secondary winding, said compensating voltage being opposed to the voltage induced in said secondary winding due to the air core reactance of said saturable type reactor.
